US00D722056S

(12) **United States Design Patent**
Nguyen et al.

(10) **Patent No.:** US D722,056 S
(45) **Date of Patent:** ** Feb. 3, 2015

(54) **DESKTOP MOBILE DEVICE DOCK**

(71) Applicant: **Mophie, Inc.**, Tustin, CA (US)

(72) Inventors: **Hien Nguyen**, Westminster, CA (US);
William Benjamin Hasbrook, Tualatin, OR (US); **Sean Michael Stuck**, Portland, CA (US); **Denny Tsai**, Temple City, CA (US)

(73) Assignee: **Mophie, Inc.**, Tustin, CO (US)

(***) Term: **14 Years**

(21) Appl. No.: **29/441,683**

(22) Filed: **Jan. 8, 2013**

(51) **LOC (10) Cl.** 14-02

(52) **U.S. Cl.**

USPC **D14/434**; D13/108
